JACKET

Sid Lawson, New City, N.Y., assignor to Sun Oil Company, Philadelphia, Pa., a corporation of New Jersey

Filed Sept. 17, 1968, Ser. No. 13,566

Term of patent 14 years

Int. Cl. D2—07

U.S. Cl. D2—183

FIG. 2.

FIG. 1.

FIG. 1 is a front view of a jacket showing my new design.

FIG. 2 is a back view of FIG. 1.

The characteristic feature of my design resides in the combination on the jacket disclosed of a plain, wide fly front, flanked on each side by a wide and narrow, contrastingly-colored diagonal stripe extending from the edge of the fly to the middle of the sleeve, substantially as shown.

I claim:

The ornamental design for a jacket, as shown and described.
